(57) **CLAIM**

The ornamental design for a crimping tool, as shown and described.

DESCRIPTION

FIG. 1 is a perspective view showing my new design for a crimping tool,

FIG. 2 is an alternative perspective thereof,

FIG. 3 is a left side view thereof,

FIG. 4 is a right side view thereof,

FIG. 5 is a front view thereof,

FIG. 6 is a rear thereof,

FIG. 7 is a top thereof; and,

FIG. 8 is a bottom view thereof.

The broken lines illustrate portions of the crimping tool that form no part of the claimed design.

1 Claim, 8 Drawing Sheets
